UNITED STATES PATENT OFFICE

GEORGE HEPBURN, JOHN TAYLOR, AND DAVID HENRY EVANS, OF LIVERPOOL, ENGLAND.

ENGINE-GOVERNOR.

SPECIFICATION forming part of Letters Patent No. 669,694, dated March 12, 1901.

Application filed March 28, 1899. Serial No. 710,823. (No model.)

To all whom it may concern:

Be it known that we, GEORGE HEPBURN, JOHN TAYLOR, and DAVID HENRY EVANS, subjects of the Queen of England, and residents of Liverpool, England, have invented certain new and useful Improvements in Engine-Governors, of which the following is a specification.

This invention has reference to governors for steam-engines for controlling the speed of same; but it has special reference to governors for marine engines (or engines where the conditions of work may be analogous) for the prevention of racing of such engines in heavy weather, owing to the lifting of the propellers more or less out of the water or variation of depth of immersion thereof, and in case of breakdown, such as breaking of the propeller-shaft, crank-shaft, propeller, or otherwise. The species of marine governor to which it belongs is that in which there is employed a weight or mass mounted upon and moved up and down by a reciprocating lever of the engine or an arm or lever worked by the engine and constructed and adapted to move the steam-governing-valve-actuating mechanism out of a normal position—viz., a position of rest when the engine is moving at the normal rate of speed—to a position in which it will actuate the steam supply or controlling valve when the engine moves above the normal rate of speed. Generally the devices moved by this weight when the governor acts consist of hinged pawls, which work in connection with and actuate a lever connected with the throttle or other governing-valve on the steam-supply pipe of the engine or other steam-pipe, as may be desired.

The object of the present invention is mainly to provide, in connection with this species of governor, improvements by which a large range of different speeds of the engine at which it may be caused to come into play or active operation is provided, and, further, to enable the adjustment or setting of the governor to accomplish this object to be performed with facility while the engines are running—that is, without having to slowdown or stop the engines.

According to this invention the object and effect is attained by the employment, in con-

nnection with the reciprocated weight, of a resistance, such as a metal or air spring resistance, which tends to prevent the weight from coming into operation, and so prevents the steam-governor-valve-actuating devices from being moved out of their normal or inactive position, such resistance being capable of being varied in degree or intensity, and the speed of the engine at which the governor would come into action may be varied at will and over a large range of variation, and, further, the spring-adjusting part of this resistance device has a mechanical gear on it, which is connected by a flexible shaft or connections leading to a part or point which is convenient, whereby while the engine is at full speed the resistance may be varied and the speed at which the governor is set to come into active operation can be changed at any moment. There is also employed in connection with this weight a supplementary weight or device so adapted as to come into action only when a very abnormal speed of the engine takes place, as in the breaking of the propeller-shaft or crank-shaft or the propeller, and which acts in connection with the main weight so as to hold and lock this weight in the position to which it has been moved at the instant of coming into action on the racing of the engine taking place.

One form or construction of resistance for effecting the purposes of this invention is illustrated in the accompanying drawings, as well as the means of adjusting its variable controlling action while the engine is in motion.

In the drawings, Figure 1 is a front elevation showing the governor; and Fig. 2 is a side elevation, partly in section, while Figs. 3 and 4 illustrate the means of adjusting the resistance while the engine is running. Fig. 5 is an elevation showing one mode of application of the governor to a marine engine.

The governor shown is in all the main points similar to the governor made by the Aspinwall's Patent Governor Company—that is to say, it comprises the main governor inertia-weight *a*, hinged and adapted to rock upon a bearing-spindle *b* on the frame *c* of the governor, an arm *d* extending out from either side of the weight and having slotted

ends, upper and lower actuating pawls or catches *e*, mounted on hinge-pins *e'* and having studs *e*² on either side fitting in the slots of the forked ends of *d*, a hooked arm *f*, projecting out from one end of *a*, a locking and releasing pawl *g*, engaging with *f*, and a releasing-lever *h*, connected with *g*. The arrangement of these parts and their actions are precisely similar to governors of this type as now commonly made and supplied, and therefore, being well known and understood, their functions and action need no description.

With regard now to the resistance device, that shown comprises a hollow tubular case *i*, having trunnions *i'* mounted and adapted to rock axially in bearings *j* on the frame-plate *c*, and this case supports a spindle *k*, part of which works within the case, while the lower end projects through the bottom of the case and rests in a socket hole or recess *l* in the upper side of the weight *a*. The spindle *k* has a collar *k'* within the case *i*, and a spring *l'* is fitted over the spindle and rests at its lower end on this collar and at its upper end bears against the screw-adjusting plug *m*, which screws into the mouth of the case *i*, its lower end pressing on the upper end of the spring *l'*. This plug *m* is bored out centrally, and the end of the spindle *k* enters this bore, so that the plug can be moved down over *k* and serves at the same time as a support for the upper end of the spindle. A lock nut or ring *n* fits over the screw-plug *m* and when screwed up holds the plug in position after the plug has been set.

It will be seen that in action the amount of resistance which will be offered to the weight *a* in its upward movement will depend upon the degree of compression under which the spring *l'* will be placed, and this degree is regulated and varied by the pressure exerted by the plug *m* on it—that is, accordingly as this plug *m* is screwed or turned farther into and out of the case *i* and compresses the spring *l'* more or less so will the resistance against the movement of the weight *a* be larger or smaller—and this spring resistance affords a large range of speeds of engine at which the governor may be adapted to come into active play. The greater the resistance of course the higher the speed of the engine will be at which the action of the governor takes place, and vice versa. In a resistance of this kind it will be plain that in lieu of a metallic spring a rubber vessel containing air at a suitable pressure may be employed within the case and adapted to act upon a spindle projecting through the lower end of the case, as the lower end of *k*, in which case, of course, by pressing upon the air more or less by screwing the plug *m* in or out the resistance will be varied.

The smaller weight referred to for holding up the weight *a* in the case of a very rapid increase of speed of the engine, due to a breakdown taking place, for keeping the

steam shut off when it has been so cut off by the weight *a* is designated *u*. It is disposed at the tail end of the weight *a* and hinged at *u'* in the bearings *v*. The normal position of this weight is that shown in the drawings, and it is held in this position—that is, prevented from falling lower—by a projection *u*², which comes against a stationary pin *u*³, projecting from one of the bearing-brackets *v*. When a very great increase of speed takes place from causes such as referred to, not only will the weight *a* move about its hinge *b* at the upper end of the first stroke of the lever on which the governor is carried, but this weight *u* will also move up, owing to its inertia of momentum, and will stand vertically over its axle-pin *u'* and directly under the lower side of the weight *a*. Thus the weight *a* cannot fall down when the end of the downstroke of the governor-lever is reached or at any time, and hence the governor valve-lever connected with the governor remains in the position it will have been moved to by the governor and the steam will be kept off and the engine brought to a standstill. To insure of this action of holding up the weight *a*, it is preferably provided with the recess at *a*², corresponding with the form of the head of the weight *u*, by which a firm engagement of these two weights under the circumstances named takes place.

Reference is now made to Figs. 3 and 4, which illustrate the means of adjusting the plug *m* and varying the resistance while the engine is in full movement. In this case at the head of the plug *m* there is a worm-wheel *o* and engaging with it a worm *p*, connected by a flexible or suitable jointed shaft *q*, of any known kind, to a point which is convenient for manipulating or working the mechanism. At this point the outer end of the flexible shaft is supported, preferably, by a fixed bearing and has upon it an actuating wheel or handle *s* and also a screwed locking-stud *t*, screwed into *r* and adapted to jam the spindle of the shaft *q* when the governor has been set. The worm *p* is fitted and carried in a suitable bracket *p'*, supported loosely on the plug *m*, this bracket and the worm *p* being prevented from turning by the legs *p*², which pass down through openings in the lugs *i*² on the case *i*.

Referring to Fig. 5, *w* designates the governor, bolted to the air-pipe lever *x* and connecting levers *y*, *y'*, *y*², and *y*³ to the main stop-valve 2.

What is claimed in respect of the herein-described invention is—

1. In a steam or other fluid pressure engine governor having an inertia weight or mass *a*, mounted by a loose joint to a reciprocating part of or connected with the engine, a variable spring resistance connected with and adapted to operate against the direction of movement of said weight when it moves due to an excess of speed of the engine, whereby a large range of speeds of said engine at which the

said weight or mass *a* is adapted to come into active operation, is afforded, a connecting device connected with and moved by said mass when operated, a stationary part, as a lever, 5 or arm, adapted to be engaged with and operated by said engaging device, and a motor-fluid-governing valve connected and operated by said stationary part, substantially as described.

10 2. In a steam-engine governor having a weight or mass *a* operated up and down by the engine, the spring resistance comprising a case *i*, a spring within the said case, screw-plug *m* adapted to act on the back end of the 15 spring, and a spindle *k* acting upon the upper side of the reciprocating weight or mass *a*, as herein set forth.

3. The improvement connected with engine-

governors consisting of the combination with an actuating weight or mass *a* operated up 20 and down by the engine; a variable spring-resistance device, having a screw-adjusting pressure device; and a flexible or jointed shaft or connection, connecting the said screw-adjusting device, with a convenient 25 point in relation thereto and gearing on the shaft meshing with gearing on said screw device.

In witness whereof we have hereunto set our hands in presence of two witnesses.

GEO. HEPBURN.
